Application December 13, 1949, Serial No. 6,592

Term of patent 14 years

(Cl. D34—15)

To all whom it may concern:

Be it known that I, Frederick E. Seyfarth, a citizen of the United States, residing at 2133 Ridge Avenue, Evanston, Illinois, in the county of Cook and State of Illinois, have invented a new, original, and ornamental Design for an Animated Animal Figure Sounding Trundle Toy, of which the following is a specification, reference being had to the accompanying drawing, forming part thereof.

Fig. 1 is a side elevational view of an animated animal figure sounding trundle toy, showing my design;

Fig. 2 is a front end elevation view thereof; and

Fig. 3 is a top plan view thereof.

I claim:

The ornamental design for an animated animal figure sounding trundle toy, as shown.

FREDERICK E. SEYFARTH.
